APPARATUS FOR PRODUCING BRANCH FITTINGS

John S. Coe, Waterbury, Conn., assignor to The Chase Companies, Incorporated, Waterbury, Conn., a corporation of Connecticut

Application April 22, 1936, Serial No. 75,699

14 Claims. (Cl. 78—63)

This invention relates to improvement in apparatus for producing branch-fittings, such, for instance, as T's, crosses, Y's, etc., for pipes and tubing.

5 The invention is primarily adapted for producing wrought-metal branch-fittings for telescopic engagement with tubes or other pipes which are designed to be sweat-soldered thereto, though it will be obvious that the T's and other branch-fittings produced by the present invention may be utilized in other types of installations.

10 One of the main objects of the present invention is to provide a superior apparatus for economically producing seamless wrought-metal branch-fittings of adequate strength and rigidity.

15 A further object is to provide a method for producing wrought-metal branch-fittings which may be carried out in a simple, reliable and effective manner, without occasioning undue wear or breakage of the apparatus employed.

20 A still further object is to provide a superior apparatus whereby branch-fittings may be produced from tubular blanks without occasioning undue thinning of the branches deflected from such tubular blanks.

25 Another object is to provide a superior method and apparatus for producing seamless wrought-metal branch-fittings rapidly and economically.

30 With the above and other objects in view, as will appear to those skilled in the art from the following, considered in conjunction with the accompanying drawings and appended claims, the present invention includes all features disclosed therein which are novel over the prior art.

35 In the accompanying drawings:

Fig. 1 is a view in side elevation of a tubular blank from which a seamless wrought-metal T may be formed in accordance with the present invention;

40 Fig. 2 is a view thereof in transverse section taken on the line 2—2 of Fig. 1;

45 Fig. 3 is a broken view mainly in elevation and partly in longitudinal section illustrating the blank in place upon one mandrel-section just prior to the insertion of the complementary mandrel-section into the said blank, and prior to the closing of the two-part die thereover;

50 Fig. 4 is a broken view partly in elevation and partly in longitudinal section showing the tubular blank in place in the apparatus just prior to applying pressure to the respective opposite ends of the said blank;

55 Fig. 5 is a transverse sectional view taken on the line 5—5 of Fig. 4;

Fig. 6 is a view corresponding to Fig. 4, but showing the material of the tubular blank deflected into the form of a T;

Fig. 7 is a transverse sectional view taken on the line 7—7 of Fig. 6;

Fig. 8 is a perspective view of one of the mandrel-sections;

Fig. 9 is a similar view of the other mandrel-section;

Fig. 10 is a broken perspective view of the 10 branch mandrel or guide-post;

Fig. 11 is a view in side elevation of the T after removal from the apparatus;

Fig. 12 is a similar view but partly in section showing the T of Fig. 11 as having its terminals 15 expanded to provide sockets for the telescopic reception of tubing or other piping;

Fig. 13 is a broken view in elevation of a section of tubing, showing the perforations thereof prior to expanding the edges of such perforations 20 in the manner indicated in Figs. 15 and 16;

Fig. 14 is a transverse sectional view taken on the line 14—14 of Fig. 13;

Fig. 15 is a view in side elevation of a tubular blank suitable for the production of crosses in 25 the apparatus of Fig. 17;

Fig. 16 is a view thereof in end elevation;

Fig. 17 is a broken sectional view of an apparatus for producing crosses, with parts of the apparatus shown in positions which they assume 30 upon the completion of the deflection of the blank into the form of a cross; and

Fig. 18 is a transverse sectional view taken on the line 18—18 of Fig. 17.

The particular apparatus herein chosen for the illustration of the present invention in Figs. 35 3 to 12 inclusive includes a pair of complementary die-blocks 20 and 21 which are held in registration with each other by suitable dowel pins 22 and which are separable from each other to 40 permit the insertion of blanks and the removal of formed T's. Each die-block is formed in its inner face with a T-shaped channel of semicircular form in cross-section comprising a main bore or channel 23 and a branch bore or channel 45 24.

When the die-blocks are engaged with each other as shown particularly well in Figs. 5 and 7, the T-shaped channel of one die-block registers with and complements the similar channel of the other die-block and forms a T-shaped channel 50 of substantially circular form in cross-section. At each of the respective opposite ends of the die-blocks, the main bore or channel 23 is enlarged to form a bearing-recess 25 accommodat- 55 ing the cylindrical bearing-portion 26 of a comp-

pression-head 27 which will be more fully hereinafter described.

Adapted to fit within the main bore 23 in the die-blocks is a two-part main mandrel, comprising 5 complementary mandrel-members or sections respectively designated as 28 and 29. The mandrel-section 28 is formed with an inwardly-extending tongue 30 having a longitudinal dovetailed rib 31 on its under face, which rib fits within 10 a similarly-extending dovetailed groove 32 formed in the upper face of a tongue 33 longitudinally offsetting from the mandrel-section 29. When the two mandrel-sections are nested together as illustrated in Figs. 4 to 7 inclusive, they provide 15 a smooth cylindrical composite mandrel over which a suitable tubular blank may be forced in a manner as will hereinafter appear.

The upper surface of the tongue 30 of the mandrel-section 28 is formed with a short radial 20 deflecting-post or boss 34, formed integral with the said tongue and having a curved deflecting-surface merging smoothly into the periphery of the latter. In its upper end the deflecting-post 34 is formed with a socket 35 adapted to snugly 25 receive a locating-tenon 36 projecting from the lower end of a branch mandrel or guide-post 37 which fits within the branch channel 24 of the die cavity.

For the dual purpose of accurately locating the 30 branch mandrel 37 in the branch channel 24 of the dies and holding the same against outward axial displacement, the said branch mandrel is formed with a rib 38 extending completely around its periphery and abutting at its upper edge 35 against a stop-shoulder 39 formed in the die-blocks 20 and 21 by constricting the outer end of the respective branch channels 24, as at 40.

The outer end of each of the mandrel-sections 28 and 29 is formed with a flange-like head 41 fitting within the interior of the compression-head 27 and on occasion engaging with an outwardly-facing stop-shoulder 42 therein. The compression-head 27 has the outer end of its bore 43 threaded for the reception of the externally-threaded flange 44 of a cap 45. Bearing at its 45 outer end against the inner face of the cap 45 is a spring 46 having its inner end bearing against the outer face of the head 41 of the adjacent one of the mandrel-sections 28 or 29 as the case may be.

Each compression-head 27 is formed at its inner end with a tubular compression-sleeve 47 having an external diameter enabling it to snugly slide against the adjacent portion of the surface of the main bore or channel 23 in the die-blocks. Similarly, the internal diameter of each of the compression-sleeves 47 is proportioned to snugly engage with a sliding fit the periphery of the mandrel-sections 28 and 29 as the case may be.

A tubular blank 48 suitable for conversion into a T is shown particularly well in Figs. 1 and 2. This tubular blank is formed of suitable wrought metal, such, for instance, as copper, brass, etc., having a suitable degree of ductility, and preparatory to its being positioned in the apparatus, it is provided about midway of its length with a lateral opening 49 located in substantially the position from which it is desired to extend a tubular branch.

The tubular blank 48 which is open at its respective opposite ends may be slipped over the tongue 30 of the mandrel-section 28 and over the deflecting-post 34 thereof by first positioning it with reference to the said tongue and post, as indicated by broken lines in Fig. 3, and then

positioning the said blank so that the deflecting-post 34 projects through the lateral opening 49 as indicated by full lines in Fig. 3.

The branch mandrel or guide-post 37 may now have its tenon 36 inserted into the socket 35 of the deflecting-post 34 and the complementary die-blocks 20 and 21 brought together over the blank and over the mandrels and compression-heads as indicated particularly well in Figs. 4 and 5. When the die-blocks are closed as just described, the branch mandrel 37 serves by means of its tenon 36 to stabilize the main mandrel which is composed of the mandrel-sections 28 and 29. The said branch mandrel is itself stabilized and accurately located by the engagement of its 1 annular rib 38 with the stop-shoulder 39 of the die-blocks and by the close-fitting of the outer portion of the branch bore or channel 24 with the portions of the periphery of the said branch mandrel located at and beyond its annular rib 38. The die-blocks 20 and 21 are held in accurate registration by the dowel pins 22 and may be firmly held against separation by any suitable holding means.

If now suitable axial pressure is applied to the faces of the caps 45 of each of the compression-heads 27 the tubular compression-sleeves 47 thereof will press upon respective opposite ends of the tubular blank and ultimately force the material of the said blank surrounding its opening 49 into engagement with the deflecting-post 35 by which latter the material will be deflected upwardly into the tubular space between the branch mandrel 37 and the branch bore or channel 24 in the die-blocks as is shown in Figs. 6 and 7. To form a T having its branch extending perpendicularly with respect to the body or run of the T, the force exerted upon the two compression-heads 27 should not only be simultaneously exerted, but should move the said compression-heads to substantially the same degree. If, however, the type of T commonly referred to as a Y is to be made, the branch-cavity in the die-blocks would be appropriately inclined and the amount of movement imparted to the respective compression-heads would naturally differ in accordance with the degree of inclination of the branch of the fitting.

It is preferable that both the periphery of the mandrels and the interior surfaces of the T-shaped channel in the die-blocks be coated with a suitable lubricant to facilitate the flow of metal as described.

The die-blocks 20 and 21 may now be unclamped and separated, as indicated by broken lines in Fig. 7, after which the branch mandrel 37 may be withdrawn from the branch 50 of the newly-formed T, which latter also includes a body or run 51 (Fig. 11). The next step in removing the T from the apparatus is to withdraw the mandrel-section 29 therefrom after which the T may be lifted sufficiently to raise its branch 50 above the deflecting-post 34, whereupon the said T may be withdrawn axially from over the tongue 30 of the mandrel-section 28 in a manner substantially reverse from that described for installing the tubular blank 48 in connection with the showing of Fig. 3.

After removal from the apparatus, the newly-formed T may have its terminals trimmed to correct any unevenness, if such unevenness exists, and if a three-way male T is desired, the T may be left in the form in which it is shown in Fig. 11. To produce bell-mouthed T's, it is only necessary to take the T of the form shown in

Fig. 11 and expand such of its terminals as may be desired to provide sockets for the telescopic reception of pipes, tubing or other fittings. In Fig. 12 is shown a T having each of its three terminals expanded to provide bell-mouthed terminals or sockets 50^a and 51^a—51^a.

In Figs. 17 and 18, an apparatus is shown for producing a type of branch-fitting commonly known as a "cross". In this apparatus, the die-blocks (only one of which is shown) are provided with a cross-shaped cavity 52, into two of the coaxial arms of which are respectively located opposed main mandrels 53 and 54. Each of the said main mandrels has mounted upon its outer 10 end a compression-head 27 of the type before referred to in connection with the preceding figures of the drawings, and the inner end of each of which main mandrels is provided with a cylindrical tenon 55 fitting into a suitable cavity formed 15 between the abutting inner ends of a pair of corresponding branch mandrels, generally designated by the numerals 56 and 57.

Each branch mandrel is of circular form in cross-section throughout its main portion and is 20 composed of three parts, including a central-member 58 and two corresponding side-members 59—59. Like the branch mandrel 37 of the apparatus previously described, the branch mandrels 56 and 57 are each formed with an annular 25 rib 60 designed to be gripped in the die-blocks.

The inner portion of the central-section 58 of each branch mandrel 56 and 57 is tapered toward its inner end where it abuts against the similar central-section of the complementary branch 30 mandrel. Each side-section 59—59 is shaped to fit its complementary tapered central-section and to produce, together therewith, a three-part mandrel of substantially-circular form in cross-section throughout the major portion of its length.

In the apparatus of Figs. 17 and 18, each side-section 59 of each of the branch mandrels 56 and 57 is formed with a lateral boss or projection 61 shaped to form one-half of a deflecting-post and 40 constituting, together with the similar projection of the abutting one of the side-sections of the other branch mandrel, a rigid deflecting-post designed to discharge the same function as the deflecting-post 34 before described.

In providing a tubular blank 62 (Figs. 15 and 50 16) for the formation of crosses, it is preferable that the said blank be formed centrally at its respective opposite sides with low embryonic branches 63—63. These embryonic branches are 55 of circular form in cross-section and may be conveniently produced by providing a length of tubing 64, shown in Figs. 13 and 14, with oval perforations 65 at diametrically-opposite points and then, by means of a balling operation or by drawing a suitable tool through such perforations in 60 a manner familiar to those engaged in the art of producing wrought-metal articles, to produce the so-called embryonic branches 63—63 of the blank shown in Figs. 15 and 16.

When the blank 62 is installed in the apparatus 65 of Figs. 17 and 18 and the compression-heads 27 are forced inwardly simultaneously and to substantially the same degree, the embryonic branches 63—63 will, as illustrated in Fig. 17, be converted into full-length branches 66—66 by 70 causing the material of the body of the said blank to flow over the oppositely-located deflecting-posts, which latter are formed as before described by the bosses or projections 61.

As will be obvious by reference to Fig. 17, the 75 main mandrels 53 and 54 may be axially with-

drawn from the newly-formed cross, preferably after the dies have been separated. Now, by first withdrawing the central-section 58 of each of the branch mandrels 56 and 57, the respective side-sections 59—59 of each mandrel may be displaced sufficiently to clear its lateral projection 61 from the main run of the cross and permit the axial withdrawal of such side-sections.

By means of the apparatus and method herein described, branch-fittings may be produced in 10 which the branches which are deflected from the blank are not unduly thinned. Furthermore, the apparatus is of a durable and low-cost character and may be operated with such facility that branch-fittings may be manufactured at a rapid 15 rate and at low cost.

The invention may be carried out in other specific ways than those herein set forth without departing from the spirit and essential characteristics of the invention and the present embodiments are therefore to be considered in all respects as illustrative and not restrictive, and all changes coming within the meaning and equivalency range of the appended claims are intended to be embraced therein.

I claim:

1. An apparatus for producing wrought-metal branch-fittings including in combination: a mandrel designed and adapted to fit within a tubular blank; a fixed non-flowing deflecting-post leading laterally from the said mandrel intermediate the ends thereof and rigidly related thereto; compressing-means movable axially with respect to the said mandrel to force the material of a tubular blank inwardly along the said mandrel and against the said rigid deflecting-post for lateral deflection thereby into cylindrical form by the force of the said compressing-means; and die-means having a channel receiving the said tubular blank and an opening leading laterally from the said channel in alignment with the said deflecting-post.

2. An apparatus for producing wrought-metal branch-fittings including in combination: a main mandrel designed and adapted to fit within a tubular blank; a fixed non-flowing deflecting-post leading laterally from the said main mandrel intermediate the ends thereof and rigidly related thereto; compressing-means movable axially with respect to the said main mandrel to force the material of a tubular blank inwardly along the said mandrel and against the said rigid deflecting-post for lateral deflection thereby into cylindrical form by the force of the said compressing means; a branch mandrel leading outwardly from the said deflecting-post; and die-means having a channel receiving the said tubular blank and an opening leading laterally from the said channel in alignment with the said deflecting-post and branch-mandrel.

3. An apparatus for producing wrought-metal branch-fittings including in combination: a two-part mandrel designed and adapted to fit within a tubular blank; a fixed non-flowing deflecting-post leading laterally from the said two-part mandrel intermediate the ends thereof and rigidly related thereto; compressing-means movable axially with respect to the said two-part mandrel to force the material of a tubular blank inwardly along the said mandrel and against the said rigid deflecting-post for lateral deflection thereby into cylindrical form by the force of the said compressing-means; and die-means having a channel receiving the said tubular blank and an

opening leading laterally from the said channel in alignment with the said deflecting-post.

4. An apparatus for producing wrought-metal branch-fittings including in combination: a two-part mandrel designed and adapted to fit within a tubular blank; a rigid deflecting-post fixed and non-flowing formed integral with and laterally off-setting from one part of the said two-part mandrel; compressing-means movable axially with respect to the said two-part mandrel to force the material of a tubular blank inwardly along the said mandrel and against the said integral deflecting-post for lateral deflection thereby; and die-means having a channel receiving the said tubular blank and an opening leading laterally from the said channel in alignment with the said deflecting-post.

5. An apparatus for producing wrought-metal branch-fittings including in combination: a two-part main mandrel designed and adapted to fit within a tubular blank; a fixed non-flowing deflecting-post leading laterally from the said two-part main mandrel intermediate the ends thereof and rigidly related thereto; compressing-means movable axially with respect to the said two-part main mandrel to force the material of a tubular blank inwardly along the said mandrel and against the said rigid deflecting-post for lateral deflection thereby into cylindrical form by the force of the said compressing-means; a branch mandrel leading outwardly from the said deflecting-post; and die-means having a channel receiving the said tubular blank and an opening leading laterally from the said channel in alignment with the said deflecting-post and branch-mandrel.

6. An apparatus for producing wrought-metal branch-fittings including in combination: a two-part main mandrel designed and adapted to fit within a tubular blank; a rigid fixed and non-flowing deflecting-post formed integral with and laterally off-setting from one part of the said two-part main mandrel; compressing-means movable axially with respect to the said two-part main mandrel to force the material of a tubular blank inwardly along the said mandrel and against the said integral deflecting-post for lateral deflection thereby; a branch mandrel leading outwardly from and interlocked with the said deflecting-post; and die-means having a channel receiving the said tubular blank and an opening leading laterally from the said channel in alignment with the said deflecting-post and branch-mandrel.

55. 7. An apparatus for producing wrought-metal branch-fittings including in combination: a mandrel designed and adapted to fit within a tubular blank; a fixed non-flowing deflecting-post leading laterally from the said mandrel intermediate the ends thereof and rigidly related thereto; compressing-means movable axially with respect to the said mandrel to force the material of a tubular blank inwardly along the said mandrel and against the said rigid deflecting-post for lateral deflection thereby into cylindrical form by the force of the said compressing-means; and a separable die having a channel receiving the said tubular blank and an opening leading laterally from the said channel in alignment with the said deflecting-post, the wall of the said opening being spaced from the said deflecting-post a distance substantially equal to the desired thickness of the material deflected from the said blank.

8. An apparatus for producing wrought-metal branch-fittings including in combination: a main

mandrel designed and adapted to fit within a tubular blank; a deflecting-post leading laterally from the said main mandrel intermediate the ends thereof; compressing-means movable axially with respect to the said main mandrel to force the material of a tubular blank inwardly along the said mandrel and against the said deflecting-post for lateral deflection thereby; a branch mandrel leading outwardly from the said deflecting-post; and a separable die having a main channel receiving the said tubular blank and a branch channel leading laterally from the said main channel and receiving the said branch mandrel, the wall of the said branch channel being spaced from the said deflecting-post and the said branch mandrel a distance substantially corresponding to the desired thickness of the material deflected from the said tubular blank.

9. An apparatus for producing wrought-metal branch-fittings including in combination: a mandrel designed and adapted to fit within the tubular blank; a fixed non-flowing outwardly-tapering deflecting-post leading laterally from the said mandrel and rigidly related thereto; compressing-means movable axially with respect to the said mandrel to force the material of a tubular blank inwardly along the said mandrel and against the said rigid outwardly-tapering deflecting-post for lateral deflection thereby into cylindrical form by the force of the said compressing-means; and die-means having a channel receiving the said tubular blank and an opening leading laterally from the said channel in alignment with the said deflecting-post.

10. An apparatus for producing wrought-metal branch-fittings including in combination: a mandrel designed and adapted to fit within a tubular blank; a fixed non-flowing deflecting-post leading laterally from the said mandrel and outwardly curved to smoothly merge into the surface of the said mandrel and rigidly related thereto; compressing-means movable axially with respect to the said mandrel to force the material of a tubular blank inwardly along the said mandrel and against the said rigid curved deflecting-post for lateral deflection thereby into cylindrical form by the force of the said compressing-means; and die-means having a channel receiving the said tubular blank and an opening leading laterally from the said channel in alignment with the said deflecting-post.

11. An apparatus for producing wrought-metal branch-fittings including in combination: a two-part mandrel designed and adapted to fit within a tubular blank; a deflecting-post leading laterally from the said two-part mandrel; interlocking-means serving to interlock the parts of the said two-part mandrel against lateral movement with respect to each other; compressing-means movable axially with respect to the said two-part mandrel to force the material of a tubular blank inwardly along the said mandrel and against the said deflecting-post for lateral deflection thereby; and die-means having a channel receiving the said tubular blank and an opening leading laterally from the said channel in alignment with the said deflecting-post.

12. An apparatus for producing wrought-metal branch-fittings including in combination: a main mandrel designed and adapted to fit within a tubular blank; a fixed non-flowing branch mandrel engageable with and disengageable from the said main mandrel and normally leading laterally therefrom intermediate the ends thereof, the said branch mandrel being formed with a

deflecting-surface merging smoothly into the surface of the said main mandrel when the said branch mandrel is in place; compressing-means movable axially with respect to the said main mandrel to force the material of the said blank inwardly along the said mandrel and against the deflecting-surface with the said branch mandrel for lateral deflection thereby; and die-means having a channel receiving the said tubular blank and an opening leading laterally from the said channel in line with the said branch-mandrel.

13. A method for producing branch-fittings including: laterally-piercing a tubular metal blank intermediate its respective opposite ends and applying endwise pressure to the said blank and deflecting an intermediate portion thereof against a fixed non-fluid deflecting-post to produce a

tubular cylindrical branch on said tubular blank solely by means of the said endwise pressure.

14. An apparatus for producing wrought-metal branch-fittings including in combination: a multipart mandrel designed and adapted to fit within a tubular blank and certain parts of which overlap and are divided from each other along a longitudinal parting-line; a fixed non-flowing deflecting-post leading laterally from the said multipart mandrel intermediate the ends thereof; compressing means movable axially with respect to the said multipart mandrel to force the material of a tubular blank against the said deflecting-post for lateral deflection thereby; and die-means having a channel receiving the said tubular blank and an opening leading laterally from the said channel.

JOHN S. COE.
